UNITED STATES PATENT OFFICE.

JOHN H. VAN WYCK, OF JERSEY CITY, NEW JERSEY.

DISH-WASHER.

1,211,985.

Specification of Letters Patent.

Patented Jan. 9, 1917.

Application filed June 21, 1915. Serial No. 35,386.

To all whom it may concern:

Be it known that I, JOHN H. VAN WYCK, a citizen of The Netherlands, residing at Jersey City, in the county of Hudson, State 5 of New Jersey, have invented certain new and useful Improvements in Dish-Washers; and I do hereby declare the following to be a full, clear, and exact description of the invention, such as will enable others skilled in 10 the art to which it appertains to make and use the same.

This invention relates to new and useful improvements in dish washers.

It is the object of the present invention to 15 provide a compact and efficient dish washing mechanism particularly adapted for use in an ordinary household, and to this end it is more specifically the object to provide such a dish washer which embodies as a 20 part thereof, a conventional form of wash boiler, so that said boiler may be used independently for other functions.

It is further the object to provide such a device wherein the dishes may be properly 25 oscillated to wash them without an objectionable splashing of the water and wherein the parts may be readily disassembled to facilitate the removal of the dishes.

It is still further the object of the invention 30 to provide such a structure which comprises a minimum number of operative parts so that it may be cheaply manufactured and will prove durable in use.

With the above and other objects and advantages in view, the invention resides more 35 particularly in the novel combination, formation and arrangement of parts more fully hereinafter described and pointed out in the appended claim.

Reference is had to the accompanying 40 drawings, wherein similar characters of reference designate corresponding parts throughout the several views, and in which:

Figure 1 is a side elevation of the dish 45 washer embodying the present invention. Fig. 2 is a top plan view thereof with the cover removed. Fig. 3 is a central vertical sectional view therethrough, and Fig. 4 is an end view of the device showing the water 50 outlet means. Fig. 5 is a section on the line 5-5 of Fig. 1. Fig. 6 is a perspective view of the actuating bar.

Referring now more particularly to the 55 accompanying drawings, the body portion of the improved dish washer is shown as comprising a conventional type of wash

boiler including the straight parallel sides 5 and the rounded end portions 6 and 7 respectively. The bottom 8 of the boiler is spaced from the bottom edges of the wall 60 portions, and the usual cover 9 is provided. Spaced arms 10 extend from the end portions and carry the usual handles 11. To adapt this wash boiler structure for use as a dish washer, the end portion 6 thereof is 65 provided with an opening 12 over which is positioned a bearing plate 13 for slidably holding a rod 14 which is adapted to extend within the boiler and reciprocate the dish holding member 15 positioned therein, a 70 suitable packing gland 16 being associated with said plate to prevent escape of water past the rod 14. The bottom of the other end portion of the boiler is provided with an opening 17, and a U-shaped plate 18 is 75 secured to the end adjacent said opening and has its inner edges offset at 19 to form guide grooves receiving a valve plate 20, to close said opening. This valve plate is preferably 80 wedge shaped as shown in Fig. 3 so as to firmly lodge in the said grooves. To readily manipulate this valve, a stem 21 is pivoted thereto and extends between the arms 10 of that end of the boiler and terminates in a 85 hand grip 22. Thus the water may be 90 readily drained from the boiler. This dish holding member 15 comprises a wire basket having straight sides 23 adapted to engage and be guided by the sides 5 of the boiler and having rounded end portions 24 to one 95 of which is secured a pair of angular arms 25 adapted to seat in recesses 26 formed in the top of the rod 14 whereby the basket is normally engaged by the rod to be reciprocated thereby and yet may be readily disengaged and removed from the casing as desired. Depending from the basket are straps 27 carrying shafts 28 having rollers 29 whereby the basket may ride easily over the bottom 8.

For reciprocating the rod 14, said rod extends outwardly of the boiler and is provided with an upstanding pin 30 which is 100 slidable in a slot 31 formed intermediately in a handle lever 32 which is pivoted at one end to an arm 33 projecting from the side of the bearing plate 13. Thus, when the dishes are placed in the basket and the cover 9 placed on the boiler, said basket may be reciprocated rapidly without any undesired 105 splashing of the water from the boiler, and without necessitating the immersion of the

operator's hands in the water at any time. Should it be desired to use the wash boiler in its normal function for washing clothes or the like, it is merely necessary to remove 5 the basket. The remaining portions which adapt it for use as a dish washer do not offer any substantial obstacle.

What is claimed is.

A dish washer including an oblong body 10 having straight parallel sides, a relatively short dish holding member in said body and provided with reticulated side and bottom walls, caster straps fixed to the bottom walls, caster rollers journaled in the straps and

holding the bottom wall in normally constant spaced relation to the bottom of the body, and reciprocating means for said dish holding member including a rod projecting into the body and engageable by the member when the rollers are on the bottom of the 20 body and disengaged therefrom when said member is lifted.

In testimony whereof, I affix my signature, in the presence of two witnesses.

JOHN H. VAN WYCK.

Witnesses:

JOHN N. FELIX,
FREDERICK BLUM.
